US00D917447S

(12) **United States Design Patent** (10) **Patent No.:** **US D917,447 S**
(45) **Date of Patent:** **** Apr. 27, 2021**

(54) **CASE FOR PORTABLE ELECTRONIC DEVICE**

(71) Applicant: **SAMSUNG ELECTRONICS CO., LTD.**, Suwon-si (KR)

(72) Inventors: **Seonkeun Park**, Suwon-si (KR); **Bumsoo Park**, Suwon-si (KR); **Hyunkeun Son**, Suwon-si (KR); **Yoonyoung Kim**, Suwon-si (KR)

(73) Assignee: **SAMSUNG ELECTRONICS CO., LTD.**, Gyeonggi-do (KR)

(**) Term: **15 Years**

(21) Appl. No.: **29/714,632**

(22) Filed: **Nov. 25, 2019**

(30) **Foreign Application Priority Data**

Jun. 14, 2019 (KR) 30-2019-0028377

(51) **LOC (13) Cl.** **14-03**

(52) **U.S. Cl.**

USPC **D14/250**

(57) **CLAIM**

The ornamental design for a case for portable electronic device, as shown and described.

DESCRIPTION

FIG. 1 is a front perspective view of a first embodiment of a case for portable electronic device, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is a front perspective view of a second embodiment of a case for portable electronic device, showing our new design;

FIG. 10 is a front view thereof;

FIG. 11 is a rear view thereof;

FIG. 12 is a left-side view thereof;

FIG. 13 is a right-side view thereof;

FIG. 14 is a top view thereof;

FIG. 15 is a bottom view thereof; and,

FIG. 16 is a rear perspective view thereof.

The broken lines in the figures depict portions of the case for portable electronic device that form no part of the claimed design.

1 Claim, 12 Drawing Sheets
